UNITED STATES PATENT OFFICE.

JOHN F. SEIBERLING, OF AKRON, OHIO.

DESIGN FOR RUBBER-TIRE MATERIAL.

SPECIFICATION forming part of Design No. 26,115, dated September 29, 1896.

Application filed July 20, 1896. Serial No. 599,978. Term of patent 14 years.

To all whom it may concern:

Be it known that I, JOHN F. SEIBERLING, a citizen of the United States, and a resident of Akron, county of Summit, and State of Ohio, have invented and produced a new and original Design for Rubber-Tire Material, of which the following is a full, clear, and exact description, reference being had to the accompanying drawings, making part of this specification.

Figure 1 is a perspective view of a piece of rubber-tire material, showing the design applied to the tread thereof; and Fig. 2 is a similar view showing the design in a slightly modified form.

The design consists of a series of obliquely-arranged ribs or corrugations on the rounded outer surface of the rubber or cushion tire material and on opposite sides of a longitudinal line or rib, the opposing ribs being reversely inclined to resemble the barbs or feathers of an arrow. The reversely-inclined opposing ribs may unite either in a central

longitudinal rib representing the shaft of an arrow, as shown in Fig. 1, or they may unite 25 directly, the longitudinal rib being omitted, as shown in Fig. 2, and form a continuous series extending the whole length of the tire material on the rounded outer face thereof, designed to constitute the wearing-surface 30 or tread of the tire when in use.

In the drawings, A indicates a section of tire material; a and a' , the reversely-inclined opposing ribs or raised surfaces representing the barbs or feathers of an arrow, and b the longitudinal rib representing the shaft thereof.

Having thus described my design, I claim—

The design for rubber or cushion tire material substantially as shown and described.

In testimony whereof I have hereunto set 40 my hand this 17th day of July, A. D. 1896.

JNO. F. SEIBERLING.
